UNITED STATES PATENT OFFICE.

LOWELL W. SHIELDS, OF ROCHESTER, NEW YORK, ASSIGNOR TO HICKOK MANUFACTURING COMPANY, INC., OF ROCHESTER, NEW YORK, A CORPORATION OF NEW YORK.

BELT BUCKLE.

Application filed August 19, 1922. Serial No. 582,931.

To all whom it may concern:

Be it known that I, LOWELL W. SHIELDS, a citizen of the United States, and resident of Rochester, in the county of Monroe and State of New York, have invented certain new and useful Improvements in Belt Buckles, of which the following is a specification.

The present invention relates to buckles and more particularly to the type in which there is provided a buckle frame with a clamping surface thereon, and a clamping member pivotally mounted on said frame and having means to cooperate with said clamping surface and also a strap end anchoring means connected thereto, an object of this invention being to provide a clamping member which may be readily stamped or pressed from sheet metal to provide a plurality of gripping edges preferably situated at different distances from the turning of the axis of the clamping member.

To these and other ends, the invention consists of certain parts and combinations of parts, all of which will be hereinafter described: the novel features being pointed out in the appended claims.

In the drawings:

Fig. 1 is a face view of a buckle constructed in accordance with this invention;

Fig. 2 is a longitudinal section through the buckle showing the clamping member in clamping position;

Fig. 3 is a perspective view of the clamping member and the anchoring means;

Fig. 4 is a longitudinal section showing the buckle shifted to release the strap end;

Fig. 5 is a perspective view of the transversely extending gripping piece;

Fig. 6 and Fig. 7 are respectively a plan view and a transverse section of another embodiment of the clamping member, showing the gripping piece formed with two gripping edges and a pivot pin held between the gripping piece and the laterally turned portion of the body of the clamping member;

Fig. 8 and Fig. 9 are similar views showing the gripping piece formed with two gripping edges and also with the pivoting means;

Fig. 10 and Fig. 11 are similar views showing the gripping piece formed with two gripping edges and secured to the body of

the clamping member in a slightly different manner from that illustrated in Figs. 8 and 9; and

Fig. 12 and Fig. 13 are similar views of still another embodiment of the invention with the gripping piece in channel form and receiving in its channel an additional gripping piece.

Referring more particularly to the drawings, 1 indicates the front plate of the buckle frame having a clamping surface 2 on its rear face and provided with rearwardly extending side flanges 3 which form the supporting means for the clamping means.

In the embodiment illustrated in Figs. 1 to 4, the clamping means embodies a main or body portion 4 which carries anchoring means, in this instance, in the form of a loop 5 for one end of a strap or belt 6. This main or body portion may be pressed or stamped from sheet metal and has a laterally extending portion 7 which, in this instance, is formed with a gripping edge 8. Abutting one face of this gripping edge is a gripping piece 9 formed with a gripping edge 10 and held in abutment with the piece 8 by headed projections 11 on such gripping piece extending through openings in the body portion 4 and upset at 12 to secure said gripping piece in position. The pivoting means, in this embodiment, is in the form of pintles 13 extending from opposite ends of the gripping piece and turning in openings in the side flanges 3 of the buckle frame.

In the embodiment illustrated in Figs. 6 and 7, the parts are the same except that the gripping piece 9^a is provided with two pressed up gripping edges 10^a and instead of providing the pivoting means on the gripping piece, a pivot pin 13^a is provided which rests on the body portion 4 at the junction of the main portion thereof with the laterally turned portion 7, the gripping piece being bent to conform to said pivot pin to confine said pivot pin in position. The gripping piece has laterally extending projections 11^a extending therefrom through openings in the laterally turned portion 7 and upset at their free ends to secure the gripping piece in place.

The embodiment illustrated in Figs. 8 and 9 is the same as that illustrated in Figs. 1 to 5 except that the gripping piece 9^b has two

gripping edges 10^b and it also has the pivoting means provided thereon in the form of pintles 13^b. The pindle piece also has laterally extending projections 11^b which extend through openings in the laterally turned portion 7 to secure the gripping piece in abutment with the laterally turned portion 7.

The embodiment shown in Figs. 10 and 11 is the same as that shown in Figs. 8 and 9 except that the gripping piece 9^c has projections 11^c extending therefrom in a plane thereof, and passing through openings in the body portion 4.

The embodiment shown in Figs. 12 and 13 has the body portion 4 formed with a short laterally turned portion 7^d which does not have a clamping edge. The gripping piece 9^d is bent into U form with gripping edges 10^d on the free ends of its two arms, a channel 14 being provided between these arms to receive a gripping piece 15. Both gripping pieces 9^d and 15 are secured in place by projections 11^d on the gripping piece 15 passed through openings in the gripping piece 9^d and the body portion 4 and having their free ends upset to secure said projections in the openings. The pivotal mounting is secured by providing a pivot pin 13^d which lies in the corner formed between the laterally turned portion 7^d and the body portion 4, the gripping member 9^d being pressed to provide a groove 16 to conform to said pivot pin.

In all embodiments of the invention, the main body portion of the clamping means may be formed from stamped or pressed material and has separate gripping pieces also adapted to be formed of stamped or pressed material and secured to such body portion. The main body portion also has a laterally turned portion which forms an abutment for the gripping piece. This laterally turned portion may or may not have a gripping edge and, if provided, this edge should preferably lie nearer to the axis of turning of the clamping means than the gripping edge on the transversely extending gripping piece. The transversely extending gripping piece may have one or two gripping edges and in one instance the two gripping edges are provided by making the gripping piece of U shape preferably with a channel between the arms in which an additional gripping piece may be arranged. The pivot means may be formed of parts of the clamping member as by providing lateral projections thereon, or, a separate pivot pin may be held between the parts of the clamping member.

What I claim as my invention and desire to secure by Letters Patent is:

1. The combination with a buckle frame having a clamping surface, of a clamping member pivoted to said frame and having a main body portion formed of sheet material

provided with a laterally turned portion and a separately formed elongated gripping piece secured to the main body portion parallel with the axis of turning of said member, abutting said laterally turned portion, and provided with a clamping edge, the main body portion having an opening formed therein on the side of the separately formed gripping piece opposite the side abutting the laterally turned portion to provide a strap anchoring loop. 70

2. The combination with a buckle frame having a clamping surface, of a clamping member pivoted to said frame and having a main body portion formed of sheet material provided with a laterally turned portion, a separately formed gripping piece secured to the main body portion parallel to the axis of turning of said gripping member, abutting said laterally turned portion and provided with a gripping edge, one of said two parts of the clamping member being provided with pintles, the main body portion having an opening formed therein on the side of the separately formed gripping pieces opposite the side abutting the laterally turned portion to provide a strap anchoring loop. 80

3. The combination with a buckle frame having a clamping surface, of a clamping member pivoted to said frame and having a main body portion formed of sheet material provided with a laterally turned portion and a separately formed gripping piece secured to the main body portion parallel with the axis of turning of said gripping member, abutting said laterally turning portion and provided with two gripping edges located at different distances from the axis of turning of the clamping member, the main body portion having an opening formed therein on the side of the separately formed gripping piece opposite the side abutting the laterally turned portion to provide a strap anchoring loop. 95

4. The combination with a buckle frame having a clamping surface, of a clamping member pivoted to said frame and having a main body portion formed from sheet material and a separately formed gripping piece secured to the main body portion parallel with the axis of turning of said clamping member and having a U shape in cross section, the edges of both arms being provided with gripping edges located at different distances from the axis of turning of the clamping member, the main body portion having an opening formed therein on the side of the separately formed gripping piece opposite the side abutting the laterally turned portion to provide a strap anchoring loop. 105

5. The combination with a buckle frame having a clamping surface, of a clamping member pivoted to said frame and having a main body portion formed of sheet material

a main body portion, an elongated gripping piece of channel form secured to the body portion and provided with gripping edges on opposite sides of the channel at different distances from the axis of turning of the clamping member, and an additional gripping piece secured in said channel and pro- vided with a gripping edge located at a different distance from the axis of turning of the clamping member than either of the gripping edges of the channeled gripping piece, and strap anchoring means secured to said clamping member. 10
